UNITED STATES PATENT OFFICE

WALTER M. NEWTON, OF DOVER, DELAWARE.

ATTACHMENT FOR WHEELBARROWS.

Application filed October 23, 1922. Serial No. 596,389.

To all whom it may concern:

Be it known that I, WALTER M. NEWTON, a citizen of the United States, residing at Dover, in the county of Kent and State of Delaware, have invented new and useful Improvements in Attachments for Wheelbarrows, of which the following is a specification.

This invention relates to hoisting apparatus and has for its object the provision of an attachment to a wheel barrow whereby it may be used as a hoisting bucket of the side dumping type, the attachment consisting of a bail with suitable brackets for connection with the wheel barrow and equipped with an attaching ring together with a latch mechanism for preventing the wheel barrow from undesired dumping or tilting.

An important object is the provision of a device of this character which will be simple and inexpensive in manufacture, easy to install, efficient and durable in service and a general improvement in the art.

With the above and other objects and advantages in view the invention consists in the details of construction to be hereinafter more fully described and claimed and illustrated in the accompanying drawings, in which:

30 Figure 1 is a side elevation of the device applied to a wheel barrow,

Figure 2 is a section on the line 2—2 of Figure 1,

Figure 3 is a front elevation and

35 Figure 4 is a detail cross section on the line 4—4 of Figure 1.

Referring more particularly to the drawings the letter A designates a wheel barrow having the usual receptacle portion B mounted upon converging bars C provided with legs D and carrying a wheel E.

In carrying out my invention I provide a U-shaped bail 10 of a length to extend beyond the ends of the receptacle B and provided at substantially its center with a clevis 11 serving as attaching means for a hoisting cable or the like.

Secured upon the bars C is a bracket 12 carrying a pin 13 which passes through a loop or eye 14 formed at the end of one arm of the bail. Secured at the forward ends of the bars C is a bracket 15 reinforced by inclined braces 16 and carrying a pin 17 received within a loop or eye 18 on the end of the other arm of the bail. By this mounting it will be seen that when the

wheel barrow is held elevated it may be tipped to one side or the other to effect dumping of the contents from the body B. It should be stated that the clevis 11 is at 60 such a position that when the loaded wheel barrow is suspended it will remain in horizontal position and the pivot points 13 and 17 should be slightly above the center of gravity of the receptacle B when loaded. 65

It is of course necessary to provide some means for preventing accidental tipping or dumping and to accomplish this I provide a leaf 19 hinged at 20 at the forward upper edge of the receptacle and formed with a 70 notch or slot 21 which engages upon the forward arm of the bail for holding the bail rigid with respect to the wheel barrow. The use of the device is obvious and it is apparent that when the wheel barrow has 75 been filled with any desired material and elevated, swinging of the leaf 19 out of engagement with the bail will permit the wheel barrow body to be tilted to one side or the other for dumping the contents. In 80 actual practice the device will be found of great advantage in a wide variety of places, for many purposes and under conditions where other hoisting apparatus is unavailable, too costly or too heavy, the device being naturally a great time and labor saver.

While I have shown and described the preferred embodiment of the invention it is of course to be understood that I reserve the right to make such changes in the form, 90 construction and arrangement of parts as will not depart from the spirit of the invention or the scope of the subjoined claims.

Having thus described my invention I claim:

1. Means for converting a wheel barrow into a dumping hoisting bucket, comprising bracket members designed to be secured upon the wheel barrow bars at the opposite ends of the receptacle body, and a bail pivotally connected with said brackets and provided with hoisting cable attaching means. 100

2. Means for converting a wheel barrow into a dumping hoisting bucket, comprising bracket members designed to be secured upon the wheel barrow bars at the opposite ends of the receptacle body, and a bail pivotally connected with said brackets and provided with hoisting cable attaching means, and means for holding the bail rigid with 110 respect to the wheel barrow body.

3. Means for converting a wheel barrow

into a dumping hoisting bucket, comprising bracket members designed to be secured upon the wheel barrow bars at the opposite ends of the receptacle body, and a bail pivotally connected with said brackets and provided with hoisting cable attaching means, and means for holding the bail rigid with

respect to the wheel barrow body, consisting of a leaf hinged upon one end of the wheel barrow body and formed with a slot engaging upon the adjacent arm of the bail. ¹⁰

In testimony whereof I affix my signature.

WALTER M. NEWTON.
